(57) **CLAIM**

The ornamental design for an animated computer mouse cover, as shown and described.

DESCRIPTION

FIG. 1 is a perspective view of our new design for an animated computer mouse cover shown in positional relation to a computer mouse, which is shown in phantom lines for illustrative purposes only;

FIG. 2 is a front end elevational view thereof;

FIG. 3 is a rear end elevational view thereof;

FIG. 4 is a side elevational view thereof, the other side being a mirror image thereof;

FIG. 5 is a top plan view thereof; and,

FIG. 6 is a bottom plan view thereof.
